United States Patent Office

Des. 178,623
Patented Sept. 4, 1956

178,623

SPOON OR SIMILAR ARTICLE

Albert Edward Allen, Utica, N. Y.

Application February 1, 1955, Serial No. 34,315

Term of patent 14 years

(Cl. D54—12)

Fig. 1 is a front view of a spoon or similar article showing my new design.

Fig. 2 is a side view thereof.

Fig. 3 is a sectional view thereof taken along lines 3—3 of Fig. 1.

The illustrated design may also be applied to other articles of flatware such as knives and forks.

I claim:

The ornamental design for a spoon or similar article, as shown and described.
